C. F. SEEKAMP

ROTATING TOPPER FOR FILLED CANS

Filed June 12, 1918

Fig. 1.

Fig. 2.

UNITED STATES PATENT OFFICE.

CONRAD F. SEEKAMP, OF NEW YORK, N. Y., ASSIGNOR TO AMERICAN CAN COMPANY, OF NEW YORK, N. Y., A CORPORATION OF NEW JERSEY.

ROTATING TOPPER FOR FILLED CANS.

Application filed June 12, 1918. Serial No. 239,639.

To all whom it may concern:

Be it known that I, CONRAD F. SEEKAMP, a citizen of the United States, residing in New York, in the county of New York and 5 State of New York, have invented a new and useful Improvement in Rotating Toppers for Filled Cans, of which the following is a specification.

This invention relates in general to top- 10 ping devices for filled cans, i. e. devices adapted to enter the cans and bring the contents thereof to a predetermined level in order that such contents may not interfere with the positioning of the closures or the 15 action of the closing machine.

A principal object of the invention is the provision of a topping device having certain smooth action, entering gradually into the can and gradually leaving it, for squeezing 20 down the contents without abrupt action.

A further and highly important object of the invention is a topping device which will enter readily into the cans and withdraw therefrom without the use of cams and other 25 auxiliary mechanism particularly provided to give to the topping device approaching and retreating movement, permitting thereby the provision of a machine with simpler and fewer parts than has been generally 30 possible in the character of machines in use prior to my invention.

Another object of the invention is the provision of a topping device having these and other advantages, which will provide ample 35 room for the feeding of the cans into accurate position upon the support of the topping devices.

Numerous other objects and advantages 40 of the invention will be apparent as it is better understood from the following description when considered in connection with the accompanying drawing illustrating a preferred embodiment thereof.

On the drawing,

45 Figure 1 is a top plan view of a topping device embodying my present invention and showing so much of the feeding mechanism of a closing machine as is necessary for an understanding of the invention; and

50 Fig. 2 is a vertical section taken centrally through said topping device showing the can support in elevation.

Referring to Fig. 1 reference character 11 indicates a rotating table or turret upon

which filled cans 12 are fed in any suitable 55 manner. This table rotates in the direction of the arrow *a* delivering the cans to a spacing table or turret 13, which in turn delivers them to the can support 14 of the topping device. The turret or table 13 is 60 provided with guides 15 and can spacers 16 of any suitable or preferred construction. The support 14 is carried upon a bearing shaft 17 passing through it and supporting 65 it for independent rotation. The support 14 in the present instance is a rotatable turret consisting of a flat can supporting circular part 18, a hub 19 which is provided with spaced can pushers 21. The hub 19 is recessed in its upper side to receive a 70 coupling sleeve 22 which forms a bearing for a slightly bevelled gear 23 locked by a pin 24 to the turret.

The toppers proper, indicated at 25, are 75 carried by an annulus 26 having arms 27 extending into a hub 28 which is mounted upon a bearing shaft 29, which shaft extends into coupling 22 and which is angularly disposed with respect to the bearing shaft 17, 80 the axes of the two shafts 17 and 29 intersecting within the coupling. The shafts 17 and 29 are rigidly connected with the coupling 22 by pins 31 which prevent rotation of either shaft. The annulus 26, arms 27 and hub 28 constitute a rotating member which 85 is driven by a bevel gear 32 meshing with the gear 23 of the support so that the toppers and support move together in circular paths in planes approaching each other at the one side to permit the toppers to enter 90 the cans for topping, and at the other side to permit the toppers to be raised a substantial distance above the can heights for feeding. The approach and retreat of the toppers with respect to the cans is along a 95 smooth, continuous arcuate path and the toppers enter the cans with an even movement. Suitable guides 33 and 34 are provided to retain the cans in the desired path of travel and they leave the topper along the 100 path 35 propelled in any suitable fashion. Driving mechanism of any desired character (not shown) is provided to rotate the toppers, which in the present instance may be considered to be a sleeve 36 extending down 105 along the shaft 17 and having upon it a collar 37 for supporting the topping device.

It is thought that the invention and many

of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

10 1 claim:

1. The combination of a can carrier moving in a fixed plane, and a topper having plunger elements to enter within cans on said carrier and arranged and turning in a fixed plane which is at an acute angle to said plane of the carrier and means for moving said carrier and topper in timed relation to each other.

2. A topping device for filled cans comprising in combination an arcuately moving can support rotatable about a vertical axis, and an arcuately moving topper for entering into the can and leveling the contents, said topper and an arc of movement of said topper lying in a fixed plane inclined with respect to the plane of the can support.

3. A topping device for filled cans, comprising in combination a support for cans moving in a single plane, and a moving topper co-operating with said support and adapted to enter the cans and also arranged and moving in a single fixed plane, said two single planes intersecting at an acute angle.

4. A topping device for filled cans, comprising in combination a support for cans moving in a single plane, and a moving topper co-operating with said support and adapted to enter the cans and also arranged and moving in a single fixed plane throughout the operative portion of its movement, said two single planes intersecting at an acute angle.

45 5. A topping device for filled cans, comprising in combination a rotating support and a rotating topping device adapted to enter into cans on said support, the plane in which said topping device is arranged and rotates being a fixed plane at an acute angle with respect to the plane of said support.

55 6. A topping device for filled cans, comprising in combination angularly disposed bearing members having their axes intersecting, a rotating support carried by one of said bearings, and a topping device carried by the other and adapted to enter the cans at a point in their travel and gearing arranged around the said bearings whereby one of said elements drives the other.

65 7. A topping device for filled cans, comprising in combination angularly disposed bearing members having their axes intersecting, a rotating support carried by one

of said bearings, and a topping device carried by the other and adapted to enter the cans at a point in their travel to depress the contents of the cans, and driving connections between said support and said topping device.

8. A topping device for filled cans, comprising in combination angularly disposed bearing members having their axes intersecting, a rotating can support carried by one of said bearings, a topping device carried by the other and adapted to enter the cans at a point in their travel for displacing parts of the contents of the cans, and can spacing and propelling members carried by said support.

9. In combination, means for feeding can bodies seriatim, and a series of plungers having means for displacing parts of the contents of the cans, said plungers being arranged in and movable along a prescribed path in a fixed plane which throughout is at an inclination to and intersects the plane of the path of the open tops of the can bodies, so that said plungers enter the can bodies at the point of intersection of said planes for levelling up the contents thereof, and means for moving the plungers in said inclined plane, substantially as described.

10. In combination a feeder for can bodies moving around a substantially vertical axis and in a horizontal plane, a series of plungers for levelling up the contents in the can bodies, and a carrier means for said plungers moving in one plane which is at an angle to the horizontal plane of movement of the feeder, whereby the plungers at one point enter the can and in their travel in said plane rise therefrom substantially as described.

11. In combination, a can body feeder, a series of topping plungers for displacing parts of the contents of the cans and carrier means for the plungers rotating throughout its course in one plane at an inclination to the plane of movement of the feeder to bring the plungers in succession into the plane of movement of the open upper ends of the can bodies, and then remove them therefrom substantially as described.

12. In combination, a feeder for can bodies rotating in a horizontal plane, a series of plungers to level up the contents in the can bodies, and carrier means therefor arranged over and substantially co-axial with the rotating feeder, said plungers being arranged and having a single movement in a fixed plane which is at an inclination to the plane of movement of the feeder, substantially as described.

13. In combination a feeder for can bodies rotating in a horizontal plane, and about a vertical axis, a series of plungers

for levelling up the contents in the can bodies, and a carrier means for said plungers moving in a plane at an angle to the plane of movement of the feeder, and arms 5 ranged over said feeder and driven by contact with said feeder, at the lowermost part of the carrier substantially as described.

14. In combination, a can feeder comprising a series of substantially radiating 10 arms rotating in a horizontal plane, a series of plungers, one for each can feeding arm with a carrier therefor rotating in a plane inclined to the plane of movement of the can feed arms and means for driving the 15 can feed arms which in turn drive the plunger carrier, substantially as described.

15. In combination, a can feeder comprising a plurality of radial arms revolving about a vertical axis, a post at said axis, 20 a series of plungers and carrier means therefor rotating in a plane inclined to the plane

of movement of the arms, said carrier being supported on the post.

16. The combination of a pair of inter-engaging gears having their planes of rotation arranged at an acute angle to each other, a rotary can carrier having connection and moving with one of said gears, a rotary topper for filled cans having its plane of rotation at an acute angle to that 25 of the can carrier and connected and moving with the other of said gears, and means for maintaining and driving said gears in the described relation to give the operative part of the topper a gradual approach to 30 and recession from the cans on the carrier.
